[57] CLAIM

The ornamental design for a horseshoe, as shown and
described.

DESCRIPTION

FIG. 1 is a top perspective view of a horseshoe showing
my new design;

FIG. 2 is a bottom perspective view thereof;

FIG. 3 is an elevational view taken from one side
thereof, the opposite side being a mirror image of the
side shown;

FIG. 4 is a front elevational view thereof; and

FIG. 5 is a rear elevational view thereof.

FIG. 1

FIG. 3

FIG. 2

FIG. 4

FIG. 5
